HENRY R. FOOTE, OF BOSTON, MASSACHUSETTS.

Letters Patent No. 98,046, dated December 21, 1869.

IMPROVEMENT IN VAPORIZING PETROLEUM, &c.

The Schedule referred to in these Letters Patent and making part of the same.

To all persons to whom these presents may come:

Be it known that I, HENRY R. FOOTE, of Boston, in the county of Suffolk, and State of Massachusetts, have invented a new and useful Means of Vaporizing Petroleum and Generating Heat; and I do hereby declare the same to be fully described in the following specification, and represented in the accompanying drawings, of which—

Figure 1 is a sectional front-end elevation of a steam-boiler, and its furnace, as provided with my invention.

Figure 2 is a vertical and longitudinal section thereof.

Figure 3 is a horizontal section of the furnace, showing the pipes for the distribution of the gaseous products of the steam and petroleum.

The main purpose of my invention is to increase the heating-powers of the furnace, and improve the combustion of its charge of fuel, particularly when the kind used is anthracite coal.

In the drawings—

A denotes a steam-boiler, of the tubular kind, arranged within a furnace, B, whose grate is shown at C.

Alongside of the furnace, and supported by a bracket, α , is a close tank or vessel for holding petroleum.

Within the fire-place of the furnace and its grate is a series of pipes, $b b b$, &c., all of which open out of and extend from a common cylindrical head, c .

Each of the pipes along its upper edge is perforated with a series of holes, arranged at, or about at equal distances asunder, and these pipes, instead of being arranged entirely above the grate, may each be disposed within one of a series of grooves made within the grate, the same being as shown at $d d$, in fig. 1.

The grooves serve to protect the pipes from being bent or injured by the fuel, and by instruments when introduced into the fuel for the purpose of effecting the discharge of ashes therefrom between the bars of the grate and into the ash-pit e ; a pipe, f , provided with a stop-cock, g , leading out of the top of the boiler and into a steam-superheating pipe, h , which goes through the fire-place and over the grate, and thence turns upward toward and over, and is passed down through the top of the petroleum-tanks, and extends nearly to the bottom of such tank or vessel.

Furthermore, a pipe, i , furnished with a stop-cock, k , leads out of the upper part of the petroleum-tank, and terminates at bottom in a discharge-cock, l .

A branch-pipe, m , leads from the lower part of the pipe i into one end of the cylindrical head or vessel c .

When the boiler is supplied with water, and the fuel is in a state of combustion in the fire-place of the furnace, and the tank is charged with liquid petroleum, the apparatus will be in a state for operation.

Steam, after having been raised in the boiler, will flow into and through the superheating-tube, where it

will be superheated, and in this state will pass into the petroleum and will vaporize it.

The steam, with the vapors of the petroleum, will thence flow into the vessel c , from whence they will find their way through the discharge-tubes into the fuel, and by being burned therewith, will not only facilitate combustion of the fuel, but produce an intense heat underneath the boiler, and thereby operate to great advantage in effecting generation of steam therein.

It is well known that when steam, of about the temperature of boiling water, is forced through petroleum, only a portion thereof, containing the lighter vapors, will be vaporized, a much higher degree of heat being required to effect the vaporization of the rest of the petroleum.

It is therefore for this purpose that I make use of superheated steam, or that heated to about 400° Fahrenheit, and by so doing, I am able to accomplish the breaking up of the petroleum.

This steam, with the oily vapors produced, I next introduce into the fire-place and among the fuel, and thereby facilitate its combustion, and effect a great increase of the heat.

I am aware of the United States patents numbered 39,918, 49,358, 54,214, and 69,253, from the subjects of which my invention, although analogous in some respects, differs materially in others; that is to say, it contains a closed petroleum-tank, arranged wholly outside of the boiler and furnace, provided with a grate for holding fuel. It also has a pipe to lead from the boiler into and through the furnace, and directly into the petroleum-tank, so as to superheat steam, and convey it, so superheated, into the petroleum of such tank, whereby the said petroleum will be vaporized in the tank, and separate from the furnace.

And furthermore, the petroleum-vapors are subsequently led from the tank by a pipe, and discharged, by a system of branch-pipes, into the furnace, and on or into the fuel, when in combustion on the grate of such furnace, all of which is not shown by any one of such patents. The vaporizing of the petroleum by superheated steam alone, in a tank outside of the furnace, is not represented in either of the subjects of the said patents.

Nor do we find, in either of such patents, any arrangement of each of the discharge-pipes b within a groove of a fuel-supporting grate of a furnace, or within the said grate and below its fuel-supporting surface, such arrangement being productive of new and useful effects.

The arrangement of the petroleum-tank outside of the furnace, and the vaporization of the contents by means of superheated steam, and the introduction of the combined steam and oily vapors, by a long pipe,

into a series of distribution-pipes arranged in the furnace, diminishes the liability of explosion of the tank, and is of advantage in other respects.

What, therefore, I claim as my invention, is as follows:

For the purpose of increasing the heat of a furnace, and improving the combustion of its charge of coal or other fuel when on its grate, the employment of superheated steam in the manner set forth, to vaporize petroleum in a vessel or tank outside of and separate from the furnace, and the introduction of the combined steam and petroleum-vapor from such vessel into the furnace, or into and over the fuel thereof when in combustion therein.

Also, the combination as well as the arrangement

of the superheating-steam pipe with the furnace, its boiler and fuel-supporting grate, the petroleum-tank, (separate from and outside of the furnace,) and the system of pipes or means of distributing the combined steam and vapor from the petroleum-tank into the furnace, and the fuel, when on the grate thereof, the whole being substantially as hereinbefore specified.

Also, the arrangement of each of the discharge-pipes *b* within a groove of the fuel-grate of the furnace, or within the grate, and below its fuel-supporting surface, the same being as hereinbefore explained.

HENRY R. FOOTE.
